PLOW SCARIFIER

Kenneth W. Porter, Charles J. Moritz, and Ernest A. Moritz, Effingham, Ill., assignors to Moritz-Bennett Corporation, Effingham, Ill., a corporation of Illinois

Application September 28, 1933, Serial No. 691,332

11 Claims. (Cl. 55—152)

Our invention relates in general to plows. It relates more in particular to a type of plow having helicoidal blades and particularly adapted for use as a scarifier, although it may have other uses 5 as an earth working instrument.

In the pending application of Joseph N. Newsom, Serial No. 652,853, a helicoidal plow possessing certain novel features is disclosed. We have discovered that a plow of this character has very 10 great advantages as a scarifier to break up a hard, tough crust of earth and the like, such, for example, as that found on oily roadways. We found that if a helicoidal blade of the character described by Newsom is controlled to move in a 15 proper manner along the ground, a very satisfactory scarifying operation can be performed. We found, however, that very definite problems presented themselves, particularly in holding the blade in proper position, avoiding side draft, and 20 in adjusting the machine to do the most satisfactory work under varying conditions.

Accordingly, the principal object of our invention is the provision of an improved plow of the character indicated.

Another object is the provision of an improved 25 instrument for scarifying a tough upper crust of earth or the like.

Another object is to counteract side draft and side sway in an instrument of this character.

A further object is the provision of improved 30 controlling means for adjusting the cutting blade to the work.

Other objects and features of the invention will 35 be apparent from a consideration of the following detailed description taken with the accompanying drawings, wherein.

Fig. 1 is a plan view showing one embodiment 40 of our invention, the view being partly broken away to conserve space;

Fig. 2 is a side elevational view thereof;

Fig. 3 is a front view;

Fig. 4 is an enlarged fragmentary sectional view taken on the line 4—4 of Fig. 1;

Fig. 5 is a fragmentary longitudinal sectional view taken on the line 5—5 of Fig. 1;

Fig. 6 is a sectional view taken on the line 6—6 of Fig. 5 showing a detail of a supporting caster wheel;

Fig. 7 is a sectional view similar to Fig. 6, but showing a modification thereof;

Fig. 8 is a fragmentary plan view showing a modification for providing an additional adjustment;

Fig. 9 is a longitudinal sectional view taken on the line 9—9 of Fig. 8;

Figs. 10 and 11 are perspective views of two parts employed in the form shown in Figs. 8 and 9;

Fig. 12 is a sectional view taken on the line 12—12 of Fig. 9;

Fig. 13 is a fragmentary plan view showing a modification of one of the control features; and

Fig. 14 is a side elevational view of Fig. 13.

While the present instrument is particularly designed for scarifying a road surface, it may have other uses. However, in order to explain the invention, reference will be made to the use of the invention as a scarifying machine.

Referring now to the drawings, we provide a main frame 12 of generally rectangular shape. A diagonal frame member 13 is secured to the main rectangular frame so as to project at two corners thereof. This diagonal frame is secured 20 to the main rectangular frame in any suitable way, as, for example, by welding. To the projecting portion of the diagonal frame 13 we secure a pair of bearing supporting members 14. These members have a widened bottom portion 25 14a (Fig. 3) to which bearings 16—16 are adjustably bolted or clamped. The bearings 16—16 journal the main blade shaft (not shown) to which the helicoidal blade sections 17 are secured. By positioning the bearings 16 at different 30 positions along the portions 14a, we can incline the helicoidal blade assembly at an angle of from 60° to 45° with the line of draft, as previously described. In the present invention, we do not show the detailed construction of the 35 blades; that is, the manner in which they are made up and secured to their shaft. In the preferred form, the individual blade sections are at an angle of from 75° to 45° to the axis of the shaft. Under all conditions, they should be at 40 an angle to the shaft of less than 90° so that when the blade as a whole is set at an angle to the line of draft, the individual blades will point substantially along the line of draft, or so that the cup portion of the blade will face into the earth rather than the back of the blade. In this manner, the proper action in the movement of earth is obtained. When looking from the forward end 45 of the blade, a right hand spiral is provided which rolls to the right as it moves through the earth. This causes the blades to work into the earth so as to move the earth into the cupped portion of the blade and provides exceptionally good results in breaking up the soil or a hard

crust which may be found on top of the soil or on top of the road.

At opposite sides of the main frame, we provide main wheels 18 and 19 journaled on crank shaped axles 21 and 22. These axles are in turn journaled in bearings 23 and 24 carried by the main frame. Each of the axles has a worm gear segment 26 (Fig. 4) engaged by a worm 27 carried on shaft 28. Each of the shafts 28 terminates in a hand wheel or crank 29. By rotating the shaft 28 and the worm carried thereby, the vertical positions of the wheels may be individually regulated. Each shaft carries an arm 31 pinned thereto and springs 32 having one end secured to the arms 31, and the opposite ends secured to the diagonal frame 13 are provided to partially offset the effect of gravity which otherwise tends to raise the wheels with respect to the frame. The frames then act in the manner of the counterweight to facilitate movement of the wheels. As shown, one of the wheels is mounted in advance of the helicoidal blade and the other to the rear of the helicoidal blade, thereby obtaining a substantial balance of the front portion of the frame.

The main frame 12 is provided with a tail extension including a generally triangular web portion 33 and a pair of channels 34. The ends of the channel members have secured thereto a tail member 36 to which a swivel member 37 is attached by suitable means such as rivets 38. A vertical swivel 39 is journaled in the member 37 and carries a fork 41 in which an axle 42 is carried. A tail supporting or caster wheel 43 is journaled on the shaft 42. The vertical swivel 39 has pinned thereto a wheel supporting member 44 of which the fork 41 forms a part. It has a web portion provided with a hole into which a pin 46 is adapted to engage. A pivoted bell crank member 47 engages the top of pin 46 and carries a removable handle 48. Through this construction, when the pin 46 engages the member 44, the caster wheel 43 is prevented from swiveling. At this time it will track directly toward the front of the machine or will be directly in line with the intended line of draft. When, however, the pin 46 is removed by pushing forward on the handle 48, the wheel is free to swivel. This is an advantage in making turns and the like, as will be shown.

As shown in Fig. 6, the caster wheel 43 is made solid and heavy. This is to provide for weight at the tail of the machine to assist in reducing side sway. The periphery of the wheel is slotted intermediate the sides thereof and a plural part disc 49 is secured to the wheel in the slot. The disc assists in maintaining the machine in line, but is removable should it be necessary to move the machine from one job to another.

As the resistance of the tail or caster wheel to side draft depends on ground friction only, extra weight and flange are added to increase this frictional resistance. The tail portion is designed to carry additional weight by means of weighted sections 51—51 attached to the channels 34. We find that by providing a relatively large amount of weight in the tail portion of the machine, resistance to side sway is increased.

In a machine of the character described, we find that the operation is improved by employing a double tractor hitch at opposite sides of the machine so that the attachment on the side of the machine nearest to the forward end of the blade is below the axis of the blade; while the attachment of the hitch at the opposite side of the frame is above the axis of the blade. One

result of arranging drawbars in this manner is to prevent any tendency of raising caster wheel off the ground which would decrease its frictional resistance.

As shown in Figs. 1 to 3, inclusive, we employ an angle 52 having one leg extending up into the channel portion of the diagonal frame member 13 and the opposite leg running vertically and carrying an angle 53. A hitching eye 54 is secured to the angle 53 below the axis of the spiral. At the opposite side of the machine, a plate 56 is secured to the frame and has a hitching eye 57 carried thereby above the axis of the spiral. A double hitch is employed including one drawbar 58 of definite length with no provision for adjustment, and another drawbar including a relatively small diameter tube 59 attached to the eye 54 and a relatively larger diameter tube 61. Pins 62 are provided to adjustably engage the two tubes together. Both tubes are flattened at the forward end and are brought together to provide a common hitch 63 for engagement by a tractor drawbar. By adjusting the members 59 and 61, various hitch arrangements may be made either to draw the scarifier directly behind the tractor or toward one side thereof as determined by conditions. By employing an offset hitch, tendency toward side sway or side movement of the scarifier is decreased.

In Fig. 7, we show a modified form of rear wheel including a main wheel body 66 and a pair of discs 67. Each of the discs is made up of a plurality of sections for easy removal from the wheel without removing the wheel from its axle. The modified wheel accomplishes the same purpose as the wheel described in the main embodiment in furnishing a support with a sufficient amount of weight to increase the force of engagement with the ground; the disc to force into the ground a sufficient distance to assist in preventing side sway; the relatively wide main wheel surface for preventing the disc from sinking too far into the ground; and the removable feature of the disc sections to provide a smooth peripheral surface when the wheel is running over a road into which it is not desired that the disc sections penetrate. The use of the two disc sections flared outwardly possess the additional advantage, however, of offering a greater resistance to side movement under certain conditions.

In Figs. 8 to 12, inclusive, we show a modification of the tail portion of the scarifier to provide for leaning the rear or caster wheel. To this end we employ two built-up structures 68 and 69 shown in Figs. 10 and 11, respectively. These two sections comprise pivoting and attaching sections and are so made up that they can be inserted in the tail section between the two channel members to constitute the tail frame and the member 36 (Fig. 5). In this way, the construction is standardized and we can provide either a leaning wheel scarifier or one without a leaning wheel from the same parts, or convert a non-leaning wheel scarifier into one with a leaning wheel by the use of some additional parts, as will be shown. The member 69 comprises a portion 69a secured by bolts 71 to the channels 34 of the tail; and a web portion 69b at right angles to the portion 69a and extending in a vertical plane when assembled on the machine. A pair of flanges 72 are integral with the webs 69a and 69b, and a tube 73 is secured between the flanges 72 and projects out slightly through the web 69b. The two flanges 72 also extend between the two channels 34 (Fig. 12) and are secured thereto by bolts 74.

which bolts also extend in and engage the tube 73. The assembly 68 includes a pair of channel members 76 secured to a vertical web section 77. A tube 78 extends through web portion 77 and is 5 securely welded thereto with sufficient clearance between tube 78 and member 76 to permit taking tail member 36 which is secured by bolts 79. The extending portion 78 projects into the tube 73 when the two members 68 and 69 are in assembled relation, and the two vertical webs 69b and 77 lie against each other. Tube 78 carries a collar 81 which is secured to a portion of the tube 78 projecting entirely through the tube 73. A pin 82 holds the collar 81 in position. The member 36, identical with the member 36 described in the main form, is bolted to the two channels 76 of the assembly member 68. The remaining portion of the tail including the swivel, castor wheel, etc., are the same as in the main form, 10 and for convenience are given the same reference characters.

In order to lean the castor wheel, the two assembly members 68 and 69 are moved with respect to each other, the movement being rotary about 15 the interconnecting tubes. To this end, the web 77 carries a projection 83; while the web 72 carries a projection 84. Nuts 86 and 87 are threaded onto right hand and left hand threaded sections, respectively, of a screw 88 provided with a hand 20 wheel 89. Each of the nuts 86 and 87 is provided with a threaded stud, and the threaded studs engage through the projections 83 and 84. Nuts 91 are threaded on the studs and complete the attachment of the studs to the projections 83 and 25 84. When the hand wheel is turned, the nuts 86 and 87 move either toward each other or away from each other, due to the provision of the left and right hand thread. Nut 87, however, being 30 in engagement with projection 84 from the assembly part 69 which is secured to the tail, is held immovable. Nuts 86 being attached to the member 68, which is free to rotate around the axis of the tubes, will be moved either to the left 35 or right and will accordingly rotate the entire assembly 68 and everything supported in back of it, including the wheel, either to left or right. This provides for leaning the rear or castor wheel.

In Figs. 13 and 14, we show a modification for raising and lowering the main frame. For convenience, only one wheel is shown to which the reference character "19" is given, as in the main form. This wheel is secured to a crank shaped axle 22 journaled in bearings 24 carried by the main frame. A pair of arms 92 are secured to 40 the axle and pivotally secured to a piston member 93 which engages in a hydraulic piston 94. This piston is pivoted at 96. A hydraulic pump 97 is operated by a pump handle 98 and delivers 45 hydraulic fluid through a pipe 99 to the hydraulic cylinder. The dotted lines in Fig. 14 show the lowered position of the wheel 19. At this time the piston has been extended by actuation of the hydraulic fluid. By releasing the pressure of hydraulic fluid, the wheel is allowed to move upwardly due to the weight of the machine. We have not shown the position of the opposite wheel, 50 but it is mounted in the same location with respect to the wheel 19 as the wheel 19 shown in Fig. 1. The dotted lines at the right of Fig. 14 indicate the position of the parts of this wheel when it is actuated.

In the operation of the machine of our invention, a suitable source of power such as a tractor is secured to the double hitch draw bar. The 55 wheels are then raised and as the scarifier is

drawn forward, the helicoidal blade works into the earth breaking up the hard top surface along a path extending the full width of the blade in a single operation. On account of the slicing action of the helicoidal blade, a heavy oiled road 5 can be broken up with the machine of our invention with only very small expenditure of power as compared to other so-called scarifiers having a tearing action which have been used to some extent trying to accomplish the same purpose. As 10 an example, our machine can be employed to break up the top surface of an oiled road with a tractor having about half the horsepower rating of a tractor required to draw an ordinary tooth scarifier cutting the same width through the same 15 road surface. The machine of our invention can operate continuously even in hot summer weather without taking the helicoidal blade out of contact with the earth. The ordinary tooth scarifier cannot be run continuously without overheating and 20 frequent sharpening of teeth is necessary. We find that due to the arrangement which we employ with the helicoidal blades, sharpening is unnecessary as the blades appear to sharpen themselves as they move through the ground. In our 25 machine the helicoidal blades have a long periphery and just a small portion of the blade is in contact with earth at any one time. This provides for constant air cooling.

An important feature of our invention is the 30 avoidance of side sway. The location and character of the hitch are important in this connection, particularly hitching one draw bar member to the frame below the axis of the helicoidal or spiral blade. The use of a relatively long tail 35 with the fixed caster wheel and a relatively large amount of weight distributed in the tail also facilitates this result. If there is a tendency toward side sway under certain conditions which may be encountered, such as the contour of a 40 road, surface and the like, the adjustable draw bar member can be regulated as to length. Ordinarily we find, however, that once this draw bar hitch is adjusted, the machine can usually be operated without further adjustment. When 45 operating on a crowned road, the machine can be drawn up either the left or right side depending upon the choice of the operator. The individual adjustment of the wheels permits bringing the blade into the work under either 50 condition.

In operating on roads, it is customary to work in sections of any convenient length. After the scarifier has been drawn over a section along one path, the handle 48 on the tail is pushed or pulled 55 forward to permit the castor wheel to swivel, the front wheels are lowered to raise the blade out of contact with the earth, and the machine is turned by merely drawing it after the tractor in a half circle. It is then brought into position 60 and operated on the opposite side of the road section and this continued a number of times, depending upon the width of the road, until finally the middle surface of the road is reached and the road left with the top surface entirely broken 65 up.

While the machine of our present invention is designed primarily as a scarifier instrument, it may be used in any connection in which a plowing and/or scarifying action is required. In 70 scarifying, the blade usually is not allowed to move deeply into the soil or roadway, the purpose usually being only to break up the hard top surface.

We accordingly do not wish to restrict our in- 75

vention to details or method of operation described, but such invention is limited only by the scope of the appended claims.

What we claim as new and desire to protect 5 by Letters Patent of the United States is:

1. In a machine of the character described, a helicoidal blade, means for supporting the helicoidal blade at an acute angle to the line of draft, a relatively long frame member extending 10 rearwardly from the helicoidal blade, a flanged caster wheel pivoted on a vertical pivot to the end of said tail, and means for holding said wheel against rotation about said vertical pivot and in direct alignment with the line of draft of 15 the machine.

2. In a machine of the character described, a helicoidal blade, means for supporting the helicoidal blade at an acute angle to the line of draft, a relatively long frame member extending 20 rearwardly from the helicoidal blade, a flanged wheel carried at the end of said tail, means for holding said wheel in alignment with the line of draft, and means for leaning said wheel sideways.

25 3. In a machine of the character described, a main frame, a helicoidal blade supported on said frame at an acute angle to the line of draft, a relatively long tail member extending from the main frame, a pair of wheels at the side of the 30 main frame, means for individually adjusting the elevation of said wheels, a caster wheel carried at the end of the tail, and means for holding said caster wheel in alignment with the line of draft of the machine.

35 4. In a machine of the character described, a helicoidal blade, means for supporting said helicoidal blade at an acute angle to the line of draft of the machine, and a two-part drawbar, one of 40 said drawbar parts being secured below the axis of the helicoidal blade and another of said parts above the axis of the helicoidal blade.

45 5. In a machine of the character described, a helicoidal blade, means for supporting the helicoidal blade at an acute angle to the line of draft of said machine, a relatively long frame tail member extending rearwardly from said blade intermediate the ends thereof, and means for supporting said tail member at the end thereof to 50 carry said member in a swivel-like action along the line of draft of the machine.

55 6. In a machine of the character described, a helicoidal blade, means for rotatably supporting said blade at an acute angle to the line of draft of said machine, a relatively long frame member extending rearwardly from the helicoidal blade intermediate the ends thereof, a wheel pivotally carried near the end of said frame member and having a flange removably secured thereto, and means for holding said pivotal wheel rigid to run 60 true to the line of draft of the machine.

7. In a machine of the character described, a

main frame of generally rectangular shape having downward extensions on either side thereof, a helicoidal blade supported on said extensions below the frame at an acute angle to the line of draft of said machine, a two-part draw bar, means 5 on said frame for securing one of said parts below the axis of the blade adjacent one end thereof, and a second means on said frame for securing said second part above the axis of the blade substantially forward of the other end of the blade 10 whereby said machine is maintained at normal operating position as it is drawn through the earth.

8. In a machine of the character described, a helicoidal blade, means for supporting the helicoidal blade at an acute angle to the line of draft and with its helixes, as followed in a direction opposite to the direction of rotation, extending toward the advanced end of the blade, a relatively long frame member extending rearwardly 20 from the helicoidal blade, a flanged wheel carried at the end of said tail, means for holding said wheel in alignment with the line of draft, and means for leaning said wheel sideways.

9. In a machine of the character described, a 25 main frame, a helicoidal blade supported on said frame at an acute angle to the line of draft, and with its helixes, as followed in a direction opposite to the direction of rotation, extending toward the advanced end of the blade, a relatively long tail 30 member extending from the main frame, a pair of wheels at the side of the main frame, means for individually adjusting the elevation of said wheels, a caster wheel carried at the end of the tail, and means for holding said caster wheel in 35 alignment with the line of draft of the machine.

10. In a machine of the character described, a helicoidal blade, means for supporting said helicoidal blade at an acute angle to the line of draft of the machine and with its helixes, as followed 40 in a direction opposite to the direction of rotation, extending toward the advanced end of the blade, and a two-part drawbar, one of said drawbar parts being secured below the axis of the helicoidal blade and another of said parts above 45 the axis of the helicoidal blade.

11. In a machine of the character described, a helicoidal blade, means for supporting the helicoidal blade at an acute angle to the line of draft of said machine, and with its helixes, as followed 50 in a direction opposite to the direction of rotation, extending toward the advanced end of the blade, a relatively long frame tail member extending rearwardly from said blade intermediate the ends thereof, and means for supporting said 55 tail member at the end thereof to carry said member in a swivel-like action along the line of draft of the machine.

KENNETH W. PORTER.
